UNITED STATES PATENT OFFICE.

PIERRE PLANTINGA, OF CLEVELAND, OHIO.

DISCHARGING DEVICE FOR VERTICAL RETORTS.

1,109,544.

Specification of Letters Patent.

Patented Sept. 1, 1914.

Application filed January 16, 1914. Serial No. 812,400.

To all whom it may concern:

Be it known that I, PIERRE PLANTINGA, a citizen of the United States, resident of Cleveland, county of Cuyahoga, and State of Ohio, have invented a new and useful Improvement in Discharging Devices for Vertical Retorts, of which the following is a specification, the principle of the invention being herein explained and the best mode in 10 which I have contemplated applying that principle, so as to distinguish it from other inventions.

My invention relates to discharging devices for vertical retorts used in the manufacture of gas, its object being to provide a device of said character which may be economically manufactured and which will perform its function in a satisfactory and efficient manner.

20 The said invention consists of means hereinafter fully described and particularly set forth in the claims.

The annexed drawings and the following description set forth in detail certain means 25 embodying my invention, the disclosed means, however, constituting but one of various mechanical forms in which the principle of the invention may be applied.

In said annexed drawings:—Fig. 1 represents a vertical transverse section of the lower end of a retort and my improved discharging device attached thereto. Fig. 2 represents a longitudinal fragmentary section of the parts shown in Fig. 1. Fig. 3 represents a horizontal section of the discharging device taken upon the plane indicated by line III—III in Fig. 1. Fig. 4 represents a fragmentary transverse section of the device illustrating a modified form 35 thereof. Fig. 5 represents a vertical transverse section of the lower end of a retort and with a modified form of my improved discharging device attached thereto. Fig. 6 represents a horizontal section taken upon 40 the planes indicated by lines VI—VI in Fig. 5. Fig. 7 represents a longitudinal axial section of the parts shown in Fig. 5.

Referring first to that form of the device illustrated by Figs. 1, 2 and 3, the illustrated 50 embodiment of my invention comprises a gas-tight casing 1, having an inclined bottom 2 terminating at an opening 3 provided with a suitable closure 4, through which opening the coke from the retort after being 55 discharged may be removed. The upper end of the casing is secured to the lower end of

the retort in a gas-tight manner and is provided with an opening 5 which registers with the lower end of the retort chamber 6. Formed in the rear of the casing and below 60 the said opening 5 is a downwardly and inwardly inclined surface 7, the lower end of which projects inwardly a short distance beyond the rear wall 8 of the casing as at 9. Immediately below the lower end portion 65 of the inclined surface 7 is a series of alined recesses 10 through the walls of which passes a supporting rod 11 the extremities of which are supported in the end walls 12, 12, 70 of the casing. Supported in suitable bearings 13, 13, secured to or formed integrally with the end walls 12, 12, is a shaft 14 parallel with the rod 11 and having its axis in a plane somewhat below the extremity 9 of the inclined surface 7. Mounted upon this 75 shaft and rotatably secured thereto in a suitable manner is a plurality of hubs 15, each of which is provided with radially extending blades 16. These blades are arranged helically with reference to each other 80 and in the longitudinal direction of the shaft, as is the usual custom in this class of devices. As illustrated, there is an odd number of sets of blades and the middle three sets may be conveniently mounted upon a 85 single hub. Each of the other hubs is formed with a circular cam 17 and similar cams 17^a, 17^a, are formed upon the middle hub. All of the hubs on the right-hand side of the middle set of blades 16 are timed so 90 as to reach their highest points successively and those on the right-hand side thereof are similarly timed. The number of recesses 10 corresponds with the number of the spaces between adjacent sets of arms and these recesses are in transverse alinement with said spaces. Having one end oscillatorily mounted upon the rod 11 and in each recess is an agitator-arm 18, the inner and free end of which extends into the alined spaces between 95 the corresponding adjacent sets of blades 16 and rests upon the corresponding cams 17, as shown in Fig. 1. One end of the shaft 14 is provided with a driving pulley 19 by means of which the shaft, cams and arms 100 may be rotated, as will be readily understood. Such rotation will effect the non-synchronous oscillation of those agitator-arms 18 which are located on one side of the middle set of blades and a similar oscillation of those blades on the other side of said set. 105

The coke coming from the bottom of the

retort falls upon the inclined surface 7 and down upon the agitator-arms and against the discharging or extracting blades 16. As the said arms 16 revolve, they catch and 5 carry the coke forwardly and discharge it into the bottom of the casing. The oscillation of the arms 18 tends to prevent the mass of coke from binding and facilitates the downward travel thereof toward the dis- 10 charging arms. By timing the circular cams differently as described, the power which it is necessary to exert to effect the oscillation, is distributed throughout one complete revolution of the shaft and thereby produces a 15 more satisfactory operation, as will be readily understood.

By employing the circular cams shown, the oscillation of the agitating arms is of a continuous and even nature. It may be de- 20 sirable in some cases to effect this oscillation in an intermittent manner and cause each one of the arms 18 to rise quickly and drop quickly and then remain in a condition of rest throughout the remainder of the shaft's 25 revolution. Where such action is desired, the shape of the cam may be varied to effect a quick rise and fall, as shown in Fig. 4, and a shelf or stop 20 may be formed on or secured to the rear wall and under each of 30 such agitator-arms. The height of each of these shelves is made such that it will support the corresponding arm throughout a portion of the revolution of the cam and permit it to remain at rest for a period of time, 35 as will be readily understood.

The above described construction may be modified as shown in Figs. 5 to 7 inclusive, by making a single recess 10^a below the lower end of the inclined surface 7 and pro- 40 viding a plate 21, one end of which is oscillatorily mounted upon the rod 11 passing through such recess and the other end of which is cut out to form a plurality of agita- 45 tor-arms 22, each one extending between two adjacent sets of blades 16, as shown in Fig. 6. This construction would require a modi- 50 fication of the timing of the cams inasmuch as all of them would have to be arranged to operate upon the arms 22 simultaneously, as shown in Fig. 7.

As will be readily understood, the structures above-described may be varied in so far as concerns the number of sets of blades and cams employed in the timing of the 55 latter without departing from the spirit of my invention.

Having fully described my invention, what I claim and desire to secure by Letters Patent is:—

60 1. In a discharging device for vertical retorts, the combination of a casing having an opening communicating with the said retort and provided with an interior down- 65 wardly inclined surface below same; a dis- charging member mounted in said casing;

agitating means located intermediately of said surface and said discharging member; and means for actuating said agitating means.

2. In a discharging device for vertical 70 retorts, the combination of a casing having an opening communicating with the said retort and provided with an interior down- 75 wardly inclined surface below said opening; an actuatable discharging member mounted in said casing; agitating means located intermediately of said surface and discharging members; and means operated by the latter for actuating said agitating means.

3. In a discharging device for vertical 80 retorts, the combination of a casing having an opening communicating with the said retort and provided with an interior down- 85 wardly inclined surface below said opening; a discharging member mounted in said casing; an oscillatable agitator located intermediately of said surface and discharging member; and means for effecting the oscil- 90 lation of said agitator.

4. In a discharging device for vertical 95 retorts, the combination of a casing having an opening communicating with the said retort and provided with an interior down- 100 wardly inclined surface below said opening; an actuatable discharging member mounted in said casing; an oscillatable agitator located intermediately of said surface and discharging member; and means operated by the latter for effecting the oscillation of said agitator.

5. In a discharging device for vertical 105 retorts, the combination of a casing having an opening communicating with the said retort and provided with an interior down- 110 wardly inclined surface below same; an actuatable discharging member mounted in said casing; agitating means comprising a plurality of independently operable members; and means for actuating the latter non-synchronously.

6. In a discharging device for vertical 115 retorts, the combination of a casing having an opening communicating with the said retort and provided with an interior down- 120 wardly inclined surface below same; a dis- 125 charging member mounted in said casing; agitating means extending from the vicinity of the lower end of said surface to said dis- charging member, and means for actuating said agitating means.

7. In a discharging device for vertical 130 retorts, the combination of a casing having an opening communicating with the said retort and provided with an interior down- 135 wardly inclined surface below same; a ro- 140 tatable discharging member mounted in said casing and comprising in its structure a plu- 145 rality of radially extending blades spaced from each other in the direction of the dis- charging member's axis; an actuatable agi-

tator extending into the space between the paths of rotation of adjacent blades; and means for actuating said agitator in said space.

5 8. In a discharging device for vertical retorts, the combination of a casing having an opening communicating with the said retort and provided with an interior downwardly inclined surface below same; a rotatable discharging member mounted in said casing and comprising in its structure a plurality of radially extending blades spaced from each other in the direction of the said member's axis; an actuatable agitator extending into the space between the paths of rotation of adjacent blades from the vicinity of the lower end of said inclined surface; and means for actuating said agitator.

9. In a discharging device for vertical 20 retorts, the combination of a casing having an opening communicating with the said retort and provided with an interior downwardly inclined surface below same; an agitator in said casing comprising a rotatable shaft having secured thereto a plurality of radially extending blades spaced from each other in the direction of the shaft's axis; an agitator consisting of a member having one end pivotally secured below the lower

end of said surface and its other end free 30 and extending into the space between the path of rotation of said blades; and a cam secured to said shaft and adapted to engage the free end of said agitator.

10. In a discharging device for vertical 35 retorts, the combination of a casing having an opening communicating with the said retort and provided with an interior downwardly inclined surface below same; an agitator in said casing comprising a rotatable 40 shaft having secured thereto a plurality of radially extending blades spaced from each other in the direction of the shaft's axis; agitating means comprising a plurality of independent agitator-arms having a common pivotal axis below the lower end of said surface, and each having a free end extending into a space between the paths of rotation of adjacent longitudinally spaced 45 blades, and cams mounted upon said shaft 50 and adapted to engage the free ends of said arms respectively.

Signed by me, this 31st day of December, 1913.

PIERRE PLANTINGA.
